DESIGN FOR A PAINT APPLICATOR OR SIMILAR ARTICLE

Lothar Sommerhauser, Long Island City, N. Y.

Application March 28, 1941, Serial No. 99,954

Term of patent 7 years

To all whom it may concern:

Be it known that I, Lothar Sommerhauser, a national of the German Reich, residing at Long Island City, in the county of Queens and State of New York, have invented a new, original, and ornamental Design for a Paint Applicator or Similar Article, of which the following is a specification, reference being had to the accompanying drawing, forming part thereof.

Fig. 1 is a top plan view of a paint applicator or similar article, showing my new design.

Fig. 2 is a side elevational view thereof.

The dominant features of the design reside in the portions shown in full lines. The front right side and top of the reservoir are substantially plain.

I claim:

The ornamental design for a paint applicator or similar article, substantially as shown and described.

LOTHAR SOMMERHAUSER.
